LOUIS R. ALBERGER, OF GREENWICH, CONNECTICUT, ASSIGNEE, BY MESNE ASSIGNMENTS,
TO ALBERGER PUMP COMPANY, OF NEW YORK, N. Y., A CORPORATION OF NEW YORK.

CENTRIFUGAL PUMP.

No. 880,956.

Specification of Letters Patent.

Patented March 3, 1908.

Application filed May 1, 1905. Serial No. 258,354.

To all whom it may concern:

Be it known that I, LOUIS R. ALBERGER, a citizen of the United States of America, and a resident of Greenwich, in the county of 5 Fairfield, State of Connecticut, have invented certain new and useful Improvements in Centrifugal Pumps, of which the following is a specification.

My present invention relates to centrifugal 10 or turbine pumps, and to a method and means of operating the same in cases where a large quantity of water or other fluid is to be lifted against a low head, and where the operating means consists of a motor having a 15 high rotative speed.

The object of the invention is to accomplish such a lift economically and effectively by a simple, novel and useful method and means; and the invention consists primarily 20 in the method of causing the flow of a portion of the fluid by the inductive action thereon of the remainder, or, in other words, of dividing the fluid to be pumped into two portions, one of which will act inductively on 25 the other so as to cause a joint discharge of the whole against a low head; and the invention also consists in the means for performing 30 this operation and in various details and peculiarities in the construction of a centrifugal or turbine pump for gaining distinct advantages over what has heretofore been possible with known forms of pumps, substantially as will be hereinafter described and claimed.

35 In the accompanying drawing illustrating my invention; Figure 1 is a side elevation of my improved centrifugal or turbine pump. Fig. 2 is a horizontal section of the same. Fig. 3 is an elevational view of a somewhat 40 modified form of the invention showing a different runner or impeller and a different kind of inlet, and also showing how the pump motor is directly attached to the driving shaft.

45 Similar numerals of reference designate corresponding parts throughout the different figures.

In the pumping of water by means of centrifugal or turbine pumps, there are found 50 many cases where a large quantity of water is to be lifted against a low head, and where it is desirable to use various kinds of high speed motors for driving the pumps. When

such motors are steam turbines depending upon a high rotative speed for efficiency and 55 economical production of power, it has been necessary to reduce the speed by means of gearing or other devices, so as to bring it down within the possibilities of the centrifugal pump. Right here, it is proper to remark that in an efficient and properly designed centrifugal pump, the peripheral speed of the runner of the pump bears a definite and direct relation to the head against which the pump is to deliver; consequently, with 60 a low head to pump against and a high speed of rotation, the proper diameter of the runner or impeller is quite small and might be less than the diameter of the supply pipe conveying 65 water to the pump, which would, of course, be an impossible and useless construction; and hence it has been found necessary, either to employ a larger runner at a great sacrifice of efficiency, or to restrict the opening through which the water is supplied 70 to the pump at a similar sacrifice of efficiency, or to resort to devices consisting of gearing or belting, or other means for reducing the speed of rotation. Hence, the object of the present invention, in producing an effective 75 pump, is to make it capable of the very high rotative speed and suitable to be driven directly from the shaft of a steam turbine or an electric motor, or other high speed prime mover. I propose to accomplish this result 80 by dividing the amount of water to be pumped into two portions, one of which is supplied to a runner larger in diameter than that required for the pumping head and having a peripheral speed sufficient to discharge 85 against a head greater than the final pumping head, and to cause this portion of the water to come into contact with the second portion of water in such a manner as to impart to the latter a velocity sufficient to discharge both portions of water jointly against 90 the final or required head.

1 denotes the discharge passage, volute, or casing, within which a runner or impeller, as 95 5, having any suitable design and construction, operates and delivers, said discharge passage having a discharge opening 4 and having the inlet pipes 2, 2, through which the water flows from the inlet 3 to both sides of the runner 5. Runner 5 is secured on the 100 shaft 6, supported in bearings 7, 7, and suit-

ably driven by any prime mover which may apply its power thereto. In Fig. 3, 10 designates a steam turbine, which applies its power to the shaft 9, on which is the runner or impeller 8, which discharges into the discharge passage 1^a. In this figure, 3^a designates the inlet through which water flows into the passages 2 and finds entrance at both sides to the runner 8. Runner 8 is of a different construction from runner 5, and is given here simply by way of furnishing an additional example of means; also the pump construction in Fig. 3 is slightly modified from that in Figs. 1 and 2, in order that a variation in the exemplification of the invention may be offered to assist further in explanation of the ideas and principles of my improvement.

Considering now, either the runner 5 which discharges into the passage 1, or the runner 8 which discharges into the passage 1^a, it will be understood that these runners are both driven at a very high rate of speed by means of the prime mover, as 10, which is a steam turbine, or which may be an electric motor or some other high-speed engine. The invention is so broad that it makes little difference what the particular form of the runner or impeller may be, or what the shape and arrangement of the adjunctive parts of the pump may be, inasmuch as the discharge passage may vary as widely as desired, and also the inlets and outlets. Hence, the impeller may be open or inclosed, or turbine or propeller blades may be used, or any other type of runner may be employed to put the first portion of water in motion. The form of the nozzle in which the inductive action takes place may be different from that shown and may be varied to meet all sorts of conditions. Remembering now that the runner rotates at a very high speed and that there is a direct relation between its peripheral speed and the head against which the pump is to deliver, and also that the quantity of water is large, and the head to be lifted against is low, I divide the water into two portions and the relative proportions of the first and second portions of water will depend upon the exact quantity of water and head to be pumped, and the exact number of revolutions per minute at which the pump is to be driven. In explaining how the water is divided into two portions, take a concrete illustration: Suppose, for instance, the quantity of water is 20,000 gallons per minute, the head 10 feet, and the revolutions 3,000 per minute. In this case the first portion of water may be 4,000 gallons per minute discharged from the runner at a speed sufficient to deliver against a head of 50 feet, which will be sufficient when the excess power is imparted to the remaining 16,000 gallons, to deliver the entire amount

of 20,000 gallons 10 feet high. With different conditions from those just given, the first portion of water may be one-half or more of the total, and it may have a velocity equal to double or less than double that necessary to discharge the whole quantity the required height.

The runner 8 in Fig. 3 has, at its periphery, an orifice or opening 11, which delivers directly into the discharge passage 1^a, and at the sides of the runner 8 are openings 12 which likewise permit a flow of the water at the sides of the impeller into the discharge passage 1^a. Obviously, when the water is divided into two parts in accordance with the principle of the present invention, one portion is pumped directly by means of the impeller 8 and is discharged through the opening 11 into the passage 1^a and this discharge being at a high speed causes an inductive action on the water with which it comes in contact, so that a flow of said latter water takes place through the openings 12; thus both portions of the water, one directly moved and the other inductively moved, pass together into the discharge passage 1^a, and the speed of flow is of such a degree as to cause all the water to be delivered to the required head, all the parts being properly proportioned to bring about this result. Referring to Fig. 2, it will be seen that the runner 5 likewise has a discharge orifice or orifices 13 which deliver into the discharge passage when pumping thereinto that portion of the water which is directly moved, while the inductively flowing water passes into the discharge way through the side passages 14 at the sides of the impeller 5.

So many changes in the details of the various mechanical parts may be made that I reserve the liberty of modifying the same within very wide limits, provided only the desired results are obtained.

In some instances, as for example in that form of the invention shown in Fig. 2, the impeller directly moves a portion of the water and delivers it into the discharge way, and at the same time an inductive action on the second portion of water is brought about and therewith also more or less of a direct action against the second portion of water, so that in this case it may be said that one portion of the fluid or liquid is pumped by direct action and another portion is moved jointly by direct action and inductive action. This direct action last referred to upon the second portion of the fluid or liquid is obviously caused by the frictional action of the outside of the impeller against the water coming through the passage.

It will of course be understood in speaking of "pumping head" and "head" to which the water is lifted or delivered that the

pumps may equally well deliver against a pressure equivalent to the pumping head with the same effect and results, with only a partial or even without any actual elevation of the water.

Having thus described my invention, what I claim as new and desire to secure by Letters Patent, is:—

1. The herein described method of operating centrifugal and like pumps, consisting in moving one portion of the fluid or liquid by direct action, and another portion by inductive action, the entire operation taking place within a single inclosure through which all the water passes and before any of the water leaves it.

2. The herein described method of operating centrifugal and like pumps, consisting in moving one portion of the fluid or liquid by direct action, and another portion both by direct action and also by the inductive action of the first portion, the entire operation taking place within a single inclosure through which all the water passes and before any of the water leaves it.

3. The herein described method of operating centrifugal and like pumps, consisting in lifting a portion of the water or other liquid to be pumped by exerting a direct action thereon, and lifting the remainder both by direct action and also by the inductive action of the first portion thereon, the entire operation taking place within a single inclosure through which all the water passes and before any of the water leaves it.

4. The herein described method of operating centrifugal and like pumps, which consists in moving a body of liquid by centrifugal force and moving another body of liquid by the motion of the former, the entire operation taking place within the pump through which all the water passes and before any of the water leaves it.

5. The herein described method of operating centrifugal and like pumps, which consists in imparting power to a body of liquid by the action of centrifugal force, and then imparting a portion of the power to another body of liquid, so as to obtain a flow of both liquids, the entire operation taking place within the pump through which all the water passes and before any of the water leaves it.

6. The herein described method of operating centrifugal pumps which consists in causing the pump impeller to directly move a portion of the water, and causing the portion so moved to inductively act upon and move another portion flowing outside the impeller, the entire action occurring within the pump and before any of the water leaves it.

7. The method of operating centrifugal pumps which consists in directly imparting

to an impeller by a steam turbine power sufficient to cause the liquid discharged by said impeller to induce the flow of an additional body of liquid, the entire operation taking place within a single inclosure through which all the water passes and before any of the water leaves it.

8. The method of operating steam turbine driven centrifugal pumps which consists in pumping one portion of the liquid by direct action and the balance by the inductive action of the first portion, the entire operation taking place within a single inclosure through which all the water passes and before any of the water leaves it.

9. The herein described method of operating centrifugal and like pumps, consisting in pumping a portion of the water directly in the midst of the entire volume of water to be pumped so as to induce a flow of the water which is not directly acted on, the entire operation taking place within a single inclosure through which all the water passes and before any of the water leaves it.

10. The herein described method of operating centrifugal and like pumps, for lifting a large quantity of water or other liquid against a low head, consisting in directly moving a portion of the water at a higher rate of speed than is necessary to overcome the final head, said movement being in the midst of the entire quantity of water so that the second portion thereof may be inductively caused to flow, for the purpose of obtaining a discharge of the whole at the desired head, the entire operation taking place within the pump through which all the water passes and before any of the water leaves it.

11. The herein described method of operating centrifugal and like pumps, for pumping a large quantity of water against a low head, consisting essentially in moving a portion of the water at high speed, in the midst of the quantity being pumped, which high-speed-moving portion inductively causes a flow of the remainder, so that the speed of the two portions is equalized and the final discharge is made at the desired head, the entire operation taking place within a single inclosed boundary through which all the water passes and before any of the water leaves it.

12. In a centrifugal or like pump, the combination with a runner or impeller, of means for introducing water at both sides, means for rotating the runner at high speed and means for permitting the water to pass around the impeller from the supply to the discharge, whereby a part of the water is directly pumped and the remainder is caused inductively to flow, the entire operation taking place within the pump inclosure.

13. In a centrifugal or like pump, the combination with a runner or impeller, of

- means for introducing water at one side, means for rotating the runner at high speed, a discharge into which the water is delivered, and a passage outside the impeller from the supply to the discharge, whereby a part of the water is directly pumped and the remainder is caused inductively to flow, the entire operation taking place within the pump inclosure.
14. In a centrifugal or like pump, the combination with a runner or impeller, of means for rotating the runner at high speed, a discharge, an inlet, all arranged to permit the flow of the water from the supply to the discharge to pass partly through the impeller and partly outside of it, whereby a part of the water is directly pumped and the remainder is caused inductively to flow, the entire operation taking place within the pump inclosure.
15. In a centrifugal or like pump, the combination with a runner or impeller, and a discharge passage into which it delivers, of means for supplying water to the impeller at both sides, means for permitting water to pass at both sides of the impeller into the discharge way, so that the impeller may act directly on a portion of the water, while the rest of the water is caused to flow by induction, the entire operation taking place within the pump inclosure.
16. In a centrifugal or like pump, the combination with an impeller, and a discharge way, said discharge way being so located relatively to the impeller that the latter may deliver directly thereinto and there may also be a delivery passage at the side of the impeller into the discharge way, means for supplying water to the impeller, so that said impeller may act directly on a portion of the water, which directly-moved portion acts inductively on the remainder, the entire operation taking place within the pump inclosure.
17. In a centrifugal pumping unit, the combination of a steam turbine supplying power to a runner, of means supplying two bodies of liquid, one acted upon by the runner and the other by the liquid discharged by the runner, the entire operation taking place within a single pump inclosure through which all the water passes and before any of the water leaves it.
18. A centrifugal pumping unit, consisting in the combination with a runner, of a steam turbine driving the same, means for supplying water to the runner, and means for allowing a lateral pass of the water by the runner, so that one body of water may be acted on by the runner and another body by the water directly discharged by said runner, the entire operation taking place within the pump inclosure.
19. In a centrifugal, turbine, or like pump, having an impeller, the combination with a discharge way, of an inlet, and means whereby part of the water passes by the impeller from the inlet to the discharge without passing through the impeller, all arranged so that a portion of the water is directly pumped, and a portion inductively pumped by the first portion, the entire operation taking place within the pump inclosure.
20. In a centrifugal, turbine, or like pump, the combination with a runner or impeller, of a discharge way, an inlet, and a passage outside the impeller from the inlet to the discharge, so that said impeller may act directly on a portion of the water, which directly-moved portion acts inductively on the remainder, the entire operation taking place within the pump inclosure.
21. In a centrifugal pumping unit, the combination of a casing, an impeller or runner, means for actuating it at a high speed, a discharge, an inlet, a water passage from the inlet to the discharge outside the impeller, the water being drawn through said passage by the inductive action of the water which is directly pumped by the centrifugal motion of the impeller, the entire operation taking place within the pump inclosure.
22. In a centrifugal, turbine, or like pump, having a runner or impeller, a discharge way into which a portion of the water is directly pumped by the centrifugal action of the impeller, an inlet supplying liquid to the impeller, and means allowing the portion of the water not passing through the impeller to pass from said inlet to the discharge, said latter portion of water being inductively acted upon by the directly-pumped portion, the entire operation taking place within the pump inclosure.
23. In a centrifugal or like pump, the combination with an impeller, of means for rotating it, a discharge, an inlet, all arranged to permit the flow of the water from the supply to the discharge to pass partly through the impeller and partly outside of it, whereby a part of the water is directly pumped and the remainder is caused to flow inductively and also by direct action, the entire operation taking place within the pump inclosure.
24. In a centrifugal or like pump, the combination of a runner or impeller, of means for introducing water at the side, means for rotating the runner, and means for permitting the water to pass around the impeller from the supply to the discharge, whereby a part of the water is directly pumped and the remainder is caused to flow both by the direct action of the impeller thereon and also by the inductive action of the first portion of water, the entire operation taking place within the pump inclosure.
25. In a centrifugal, turbine, or like pump,

having an impeller, the combination with a discharge-way, of an inlet, and means whereby part of the water passes by the impeller from the inlet to the discharge without 5 passing through the impeller, all arranged so that a portion of the water is directly pumped by the impeller, and a portion pumped jointly by direct action and by the

inductive action of the first portion of water thereon.

Signed at New York this 27th day of April, 10
1905.
